UNITED STATES PATENT OFFICE.

CLAUDIA KORP, OF ROBINSON, ILLINOIS.

AUXILIARY BED.

Application filed October 19, 1921. Serial No. 508,757.

To all whom it may concern:

Be it known that I, CLAUDIA KORP, a citizen of the United States, and a resident of Robinson, in the county of Crawford 5 and State of Illinois, have invented a new and useful Improvement in Auxiliary Beds, of which the following is a full, clear, and exact description.

My invention relates to auxiliary beds, 10 and it consists in the combinations, constructions, and arrangements herein described and claimed.

An object of my invention is to provide an auxiliary bed which may be folded up 15 and slidably disposed beneath an ordinary type of bed, free from the floor, while not in use.

A further object of my invention is to provide an auxiliary bed that is always accessible to one using an ordinary type of bed, yet entirely out of the way when not in use.

A further object of my invention is to provide a device of the character described 25 that is simple to operate, that is durable, and thoroughly practical commercially.

Other objects and advantages will appear in the following specification, and the novel features of the invention will be particularly 30 pointed out in the appended claims.

My invention is illustrated in the accompanying drawings forming part of this application, in which—

Figure 1 is a sectional view of an ordinary bed with the auxiliary bed in a retracted position,

Figure 2 is the same as Figure 1, but with the auxiliary bed extended,

Figure 3 is a view of the auxiliary bed 40 in the final operative position,

Figure 4 is a top plan view of both beds, the auxiliary bed extended,

Figure 5 is a fragmentary view of one 45 of the tracks and one of the rear hangers,

Figure 6 is a fragmentary view of one of the tracks and one of the forward hangers.

In carrying out my invention, I make use 50 of the ordinary type of bed 1 which may be of metal, wood, or of any ordinary construction such as is common to the art. I suspend from the horizontal mattress-bearing frame 2 a pair of metal tracks 3 having 55 longitudinal slots 4 extending substantially

the entire lengths thereof. The metal tracks 3, as reference to Figure 1 will show, are bent upwardly adjacent one end thereof and hooked as shown at 2' to the bed frame aforementioned. At the opposite end of 60 the tracks 3 is an outwardly extending portion 5 comprising an end surface 6 and a top surface 7 bent back parallel to the track 3. The slot 4 is arranged to extend up through the surface 6 and the surface 7. 65 Adjacent the end of the surface 7 is an upwardly extending flange 8 having a hook shaped portion 9 at the end thereof for fastening this end of the track to the frame 2 of the bed 1.

An auxiliary bed frame 10 is provided with two substantially T-shaped hangers 11 at one side thereof. The hangers 11 are pivotally mounted on the frame 10, as shown at 12, and are suspended at their 75 opposite ends from the tracks 3, the cylindrical portion 13 of the hangers passing through the slots 4 and the T-shaped head 14 resting upon the upper surface of the tracks 3. The hangers 11 are free to slide 80 lengthwise the tracks 3.

The frame 10 of the auxiliary bed has pivotally mounted at each end thereof end pieces 15 and a side piece 16. The end pieces 15 are arranged to hinge away from 85 the frame and downwardly when not in use. The side piece 16 is arranged to hinge down upon the frame 10 when not in use. Two T-shaped hangers 17 are disposed on the frame 10 at right angles thereto, and are in 90 a vertical position when the side 16 is folded down upon the frame 10. These hangers 17 have substantially square head portions 18 which are arranged to enter and pass through recesses 19 in the slot 4 on the surface 6 of the tracks. It will be seen therefore that the hangers 17 may be placed and removed from suspension upon the track 3 at will.

Legs 20 are provided at the outer side of 100 the auxiliary bed and are pivotally attached to the frame 10, as shown at 21. These legs 20 are arranged to fold up flat against the frame 10 of the auxiliary bed when not in use. This is shown in Figures 1 and 2.

From the foregoing description of the various parts of the device, the operation thereof may be readily understood. Normally the auxiliary bed, when not in use, is in the retracted position shown in Figure 1, the 110

hangers 11 supporting the bed at one side and the hangers 17 supporting it at the other.

When it is desired to use the auxiliary bed the outer portion at some point adjacent the hangers 17 is gripped and the bed manually extended to the position shown in Figure 2. This may be done since the hangers 11 are arranged to slide along the tracks 3. The end pieces 15 and the side piece 16 are then elevated and secured together at their corners by a locking means, as shown at 22.

It will be noted at this time that the auxiliary bed lies in a plane lower than the plane of the mattress on the bed 1. The auxiliary bed must be elevated in some way to bring the two beds in the same plane. To this end the hangers 11 make possible the swinging of the bed from a suspended position to a supported position, as shown in Figure 3, the heads 14 of the hangers 11 merely acting as pivotal members upon the tracks 3.

The legs 20 are now unfolded from the frame 10 and are used to support the outer side of the auxiliary bed.

For the sake of more clearly revealing the construction of my invention, the mattress and bedding is not shown on the auxiliary bed. It will readily be seen, however, that the bedding need not be removed when the auxiliary bed is in a retracted position. A low side 23 of the auxiliary bed adjacent the larger bed aids in preventing the shifting of the bedding upon the frame 10. This side 23 is clearly shown in Figures 1 and 2.

I claim:

1. In a device of the character described, an auxiliary bed frame, a plurality of hangers pivotally mounted on said frame at one side thereof, a plurality of vertical hangers rigidly mounted on said bed frame, and a plurality of track members adapted to be secured to the under surface of a bedstead, said first named hangers being adapted to engage and slide upon said track, said second named hangers being adapted to engage said track at will and to slide thereupon. 50

2. The combination with a self-supporting bed having a horizontal frame, of a plurality of track members suspended from the under surface of said frame, an auxiliary bed frame, and means associated with said tracks permitting said auxiliary bed frame to be suspended beneath said first named bed or extended to the side and on a level with the frame of said first named bed at will, said means comprising a plurality of hangers pivotally mounted on said auxiliary bed frame at the inward side thereof, side and end walls pivotally mounted on said auxiliary bed frame, a plurality of vertical hangers rigidly mounted on said auxiliary bed frame, and a plurality of legs hingedly mounted on said auxiliary bed frame for supporting said last named frame when extended, said first hangers being slidably supported by said track members and said last named hangers having slidable support from said track members and being removable therefrom. 70

CLAUDIA KORP.
